(57) **CLAIM**

The ornamental design for a package, as shown and described.

DESCRIPTION

FIG. 1 is a front, right side perspective view of a package showing our new design;

FIG. 2 is a front elevational view of FIG. 1, the rear and side elevational views being identical;

FIG. 3 is a top plan view of FIG. 1;

FIG. 4 is a bottom plan view of FIG. 1;

FIG. 5 is a front perspective view of a package shown in a position of use with an exemplary planter;

FIG. 6 is a front elevational view of FIG. 5, the rear and side elevational views being identical;

FIG. 7 is a top plan view of FIG. 5;

FIG. 8 is a bottom plan view of FIG. 5;

FIG. 9 is a front perspective view of a package shown in a position of use with an exemplary hose bowl;

FIG. 10 is a front elevational view of FIG. 9, the rear and side elevational views being identical;

FIG. 11 is a top plan view of FIG. 9;

FIG. 12 is a bottom plan view of FIG. 9;

FIG. 13 is an exploded perspective view of the package showing all package components.

FIG. 14 is an exploded top plan view of the package showing all package components side by side;

FIG. 15 is an exploded front elevational view of the package showing all package components; and,

FIG. 16 is an exploded bottom plan view of the package showing all package components side by side.

The broken lines are shown for the purpose of illustrating environmental subject matter which forms no part of the claimed design.

1 Claim, 8 Drawing Sheets
